HEINRICH SCHRÖDER, OF BERLIN, GERMANY, ASSIGNOR TO GESELLSCHAFT FÜR DRAHTLOSE TELEGRAPHIE M. B. H. HALLESCHES UFER, OF BERLIN, GERMANY, A CORPORATION OF GERMANY

FINE ADJUSTMENT DEVICE FOR RADIO APPARATUS

Application filed December 11, 1924, Serial No. 755,125, and in Germany December 20, 1923.

The present application relates to an arrangement for precise and fine adjustment of tuning means, as variable condensers, variometers, and the like, particularly for amateur radio receivers. The arrangement guarantees special simplicity, cheapness and reliability.

These and other objects will be apparent from the following description and claims when considered with the accompanying drawing in which:

Fig. 1 is a section thru a panel showing the main dial for the usual course adjustment with my improved device for giving fine adjustment.

Fig. 2 shows a detail of the structure of my device.

Fig. 3 is a section thru a panel showing my device, the section being at right angles to Fig. 1.

Fig. 4 is a section on the line 4—4 of Fig. 1.

Referring to the drawing, P is the usual panel board having an opening 1 to accommodate shaft 2 of a piece of apparatus (not shown) mounted thereon. On the outer end of shaft 2 is the usual dial b and knob a for the usual course adjustment, the knob and dial being fixed to shaft 2 in any desired manner. The dial b has teeth 3 formed on its outer edge.

Near the opening 1 is a second opening 4 for accommodating the shaft 5 and bent strip e. The plate 6 is fixed to the front side of panel P over opening 4 and has a slot f there-in running radially with respect to dial b.

Fixed to plate 6 is bent elastic strip e shown developed in Fig. 2. The larger end of strip e is bent to provide a projection 7. This projection 7 is secured to plate 6 along one side of slot f in any desired manner. The strip e is bent to form midway of its length a bowed portion 8. The smaller end of strip e is bent to form a projection h, the function of which will be described in detail below.

The shaft 5 has journals 9 and 10, the journal 9 turning in bearing i formed in the bowed portion 8 and journal 10 having rotative motion and also sliding motion in slot f. The shaft 5 also has formed thereon a spur

gear d for meshing with teeth 3 on dial b and has also a small knob c suitably secured thereto.

The end h of strip e has two tapered surfaces 11 and 12 having a cam or wedging action on a reduced portion 13 of shaft 5. Due to the elasticity of the bent spring strip e, the end h is continually urged to approach the projection 7 and therefore cam surface 11 or 12 continually urges the shaft 5 away from or towards the dial b, according to which surface is bearing on the reduced portion 13.

It will easily be understood that either cam surface 11 or 12 may be selectively brought into bearing engagement with reduced portion 13 by forcing the knob c in either direction of the double pointed arrow x against the thrust of the surface which happens to be operating on it, until it over-rides the intersection of the surfaces 11 and 12. Also the projection h which is always in engagement with reduced portion 13 effectively holds shaft 5 from movement longitudinally of its axis.

Therefore the present application represents not only a simple arrangement for accurate adjustment of tuning means, but has the further advantage that the arrangement at the same time is used for fixing the dial by means of a suitable gearing, so that no unintended shifting of the dial can be caused by handling the receiving apparatus. As the complete arrangement for vernier adjustment consists only of a knob, a shaft, a spring strip and a cover plate, it is very cheap. Since the cam surface 12, when in engagement with reduced portion 13, always urges the gear d into engagement with the teeth 3 on dial b, this action takes care of any inaccuracy or eccentricity of the dial b.

Having described one embodiment of my invention, I am entitled to all modifications thereof as fall fairly within the scope of the following claims:

1. The combination of a tuning dial with an adjustable vernier adjustment device and a yieldable cam member having two cam surfaces adapted to maintain said device in operative or inoperative relationship to said dial.

2. In combination, a rotary tuning dial, a vernier adjustment device adapted to engage the periphery of said dial and a member for maintaining said vernier device in operative or inoperative position, said member being fixed at one end and provided at the other end with a cam face for engaging said vernier device.
3. In combination, a rotary tuning dial, a vernier adjustment device adapted to engage the periphery of said dial and a yieldable cam member for continuously urging said device toward its operative or inoperative position.
4. In combination, a toothed rotary tuning dial, an adjustable vernier adjustment device comprising a knob having a depending co-operative gear and shaft, and a single yieldable means having a double cam surface at one end, said cam surface acting to engage said shaft to maintain said device in either an operative or an inoperative relationship with said dial.
5. In combination, a toothed rotary tuning dial, an adjustable vernier adjustment device comprising a knob having a depending co-operative gear and shaft, and a single yieldable means adapted to maintain said device in an operative or inoperative relationship with said dial, said means consisting of a slotted plate and a curved spring attached thereto and forming a bearing for said shaft.
6. In combination, a toothed rotary tuning dial, an adjustable vernier adjustment device comprising a knob having a depending co-operative gear and an annularly grooved shaft, and a single yieldable means adapted to maintain said device in an operative or inoperative relationship with said dial, said means consisting of a slotted plate and a curved spring attached thereto and forming a bearing for said shaft, said spring being adapted to contact with the grooved portion of said shaft.
7. The combination according to claim 6, in which said slotted plate is arranged with the slot radial to said tuning dial, and in which said curved spring is attached at one end to said plate and is provided at its free end with cam surfaces which act to move said shaft in said slot to maintain the operative or inoperative relationship between said dial and said device.
8. In combination a rotary element, a vernier device for said element, said device being movable into and out of operative position, and a cam member fixed at one end for automatically urging said device toward the extreme of its moved position.

HEINRICH SCHRÖDER.
